UNITED STATES PATENT OFFICE.

LAURA DEL FARO AND ANNA LANDMESSER, OF LOS ANGELES, CALIFORNIA.

DESIGN FOR A SMOKER'S TRAY.

Application filed August 24, 1927. Serial No. 23,192. Term of patent 8½ years.

To all whom it may concern:

Be it known that we, LAURA DEL FARO and ANNA LANDMESSER, citizens of the United States, residing at Los Angeles, in the county of Los Angeles and State of California, have invented a new, original, and ornamental Design for Smokers' Trays, of which the following is a specification, reference being had to the accompanying drawing, forming part thereof.

The figure is a perspective view of a smoker's tray showing our new design.

We claim:

The ornamental design for a smoker's tray, as shown.

LAURA DEL FARO.
ANNA LANDMESSER.
